G. W. BARTLETT

BURNER

Filed April 4, 1923

Inventor

George W. Bartlett
Watson & Coleman
Atty

UNITED STATES PATENT OFFICE.

GEORGE W. BARTLETT, OF TACOMA, WASHINGTON, ASSIGNOR TO BARTLETT OIL BURNER & POWER COMPANY, A CORPORATION OF WASHINGTON.

BURNER.

Application filed April 4, 1923. Serial No. 629,831.

This invention relates to certain improvements in burners and has relation more particularly to a device of this general character wherein a liquid fuel is atomized and delivered in the form of spray through the medium of an expansible fluid and it is an object of the invention to provide a device of this general character having novel and improved means whereby the flame of the 10 burner is under automatic control.

It is also an object of the invention to provide a novel and improved burner of this general character wherein auxiliary or supplemental means are provided for comminuting or breaking up the fuel whereby a maximum of efficiency is obtained.

The invention consists in the details of construction and in the combination and arrangement of the several parts of my improved burner whereby certain important advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying drawings, wherein:—

Figure 1 is a view partly in section and partly in elevation of a burner constructed in accordance with an embodiment of my invention;

35 Figure 2 is an enlarged fragmentary sectional view taken substantially on the line 2—2 of Figure 1;

Figure 3 is a fragmentary sectional view taken substantially on the line 3—3 of Figure 2.

As disclosed in the accompanying drawings, 1 denotes a casing providing a mixing chamber 2 herein disclosed as substantially spherical in form. In communication with the chamber 2 is a depending nipple 3 forming a continuation of an oil supply line 4. Interposed in the line 4 is a valve 5 of a globe type and which is provided with the exteriorly disposed valve stem 6. The cas-

ing 1 is provided with the opposed nipples 7 in communication with the chamber 2 and coupled to the outer nipple 7 is an elongated tubular member 8. Fixed to the outer portion of the member 8 is the tip 9 provided with a restricted discharge vent 10. The

outer end portion of the tip 9 is also provided adjacent to the vent 10 with the supplemental or auxiliary vent 11 in communication with a chamber 12 comprised in the structure of the tip 9. 14 denotes a pipe line in communication with the chamber 12 and leading from a pipe line P in communication with a steam boiler. Flow through the pipe 14 is under control of the valve 15 of any ordinary or preferred construction.

Extending within the chamber 2 through the second or inner nipple 7 is a tube 16 which closely approaches the inserted end portion of a second tube 17 directed through the first nipple 7. The outer end portion of the tube 16 is flared or enlarged to provide a valve seat 18.

Coupled in a conventional manner to the inner or second nipple 7 is an L-joint 19 also in communication with the pipe line P. The flow through the pipe line P and the coupling 19 is under control of the valve 20 of any ordinary or preferred type.

Coacting with the valve seat 18 is a needle valve 21 supported for sliding movement by the coupling 19 and which has an extended end portion engaged with a block or sleeve 22. This sleeve 22 carries an outstanding pin 24 which provides a support for an upstanding lever 25.

Also connected to the block or sleeve 22 is a rod 26, said rod 26 being aligned with the needle valve 21. This rod is slidably disposed within a cylinder 27 spaced from the coupling 19 but herein disclosed as connected thereto by a web 28 whereby the cylinder 27 has a fixed position relative to the coupling 19. The outer end portion of the cylinder 27 is enlarged as at 29 and at which enlarged portion 29 is arranged a head 30 carried by the inserted end portion of the rod 26.

The enlarged portion 29 of the cylinder 27 is closed by a cap 31 whereby a chamber 32 is provided. This chamber 32 is intersected by a diaphragm 33 preferably of phosphor-bronze and with which the head 30 is in direct contact.

A pipe 34 leads from the pipe P at a point outwardly of the valve 20 and is in communication with the chamber 32 at the side of the diaphragm 33 opposite to the head 30. Arranged within the cylinder 27 is a tension spring 35, one end portion of which is in direct contact with the head 30.

while the opposite end portion is in contact with an enlargement 36 slidably mounted upon the rod 26. Coacting with the enlargement or head 36 is a member or nut 37 threaded through the inner end of the cylinder 27 and which provides means whereby the tension of the spring 35 may be regulated or adjusted as the occasions of practice may prefer.

10 The upper end portion of the lever 25 as hereinbefore referred to is pivotally connected with an end portion of an arm 38, the opposite end portion of which is pivotally engaged with the wall of the enlarged portion 29 of the cylinder 27. The lower portion of the lever 25 is pivotally engaged with a block 39 slidably mounted upon the outer end portion of the rod 6. The rod 6 inwardly of the block 39 is provided with 15 an enlargement 40 and interposed between said enlargement 40 and the block 39 is a spring 41 herein disclosed as encircling the rod 6. The spring 41 serves as a cushion and at the same time facilitates the rocking movement of the lever 25 in one direction.

20 The pipe line P preferably leads from a steam boiler with which the burner is associated and the normal steam pressure delivered through the branch pipe 34 within the chamber 32 is the same as the tension of the spring 35 so that under such normal conditions the valve 21 and the valve 5 are open to effect the desired mixture. The steam from the boiler also passes from the pipe P and through the sleeves 7 and which action results in oil being drawn up into the chamber 2 through the pipe line 4 and through the vent 10 of the tip 9. As the boiler pressure increases, the diaphragm 33 25 will impose corresponding movement to the head 32 and rod 26 whereby the valves 21 and 5 will be correspondingly closed and to an extent to reduce the flame to only a pilot. Upon decrease of the boiler pressure, the 30 valves 6 and 15 will move in the opposite direction resulting in a correspondingly enlarged flame.

When the valve 15 is open the steam discharged through the vent 11 will serve to strike the mixture discharged through the 50 vent 10 and thereby further break and comminute the fuel, such as oil, and thus assuring maximum efficiency of the fuel.

From the foregoing description it is thought to be obvious that a burner constructed in accordance with my invention is particularly well adapted for use by reason of the convenience and facility with which it may be assembled and operated, and it will also be obvious that my invention is 55 susceptible of some change and modification without departing from the principles and spirit thereof and for this reason I do not wish to be understood as limiting myself to the precise arrangement and formation of 60 the several parts herein shown in carrying out my invention in practice except as hereinafter claimed.

I claim:—

65 In combination with a pressure line, a burner in communication therewith, a reciprocating valve for controlling flow from the pressure line into the burner, an oil supply line leading to the burner, a reciprocating valve for controlling flow through said 70 oil supply line, a cylinder, a head within the cylinder, a line connecting the pressure line and the cylinder and moving said head in one direction, a rod operatively connected with the head and the first named valve 75 whereby the head and valve move in unison, an arm supported adjacent to the cylinder, a lever pivotally connected with the arm, a stem for the second named valve, a block 80 slidably mounted on the stem and with which the lever is pivotally engaged, means for pivotally connecting the lever intermediate its first named pivotal connections with the rod, and means for cushioning the 85 movement of the block in one direction. 90

In testimony whereof I hereunto affix my signature.

GEORGE W. BARTLETT.
